UNITED STATES PATENT OFFICE.

WALTER TAYLOR, OF EUREKA, CALIFORNIA.

PANTS-STRETCHER.

1,232,994.

Specification of Letters Patent. Patented July 10, 1917.

Application filed May 3, 1916. Serial No. 95,204.

To all whom it may concern:

Be it known that I, WALTER TAYLOR, a citizen of the United States, residing at Eureka, in the county of Humboldt, State 5 of California, have invented a new and useful Pants-Stretcher; and I do hereby declare the following to be a full, clear, and exact description of the invention, such as will enable others skilled in the art to which 10 it appertains to make and use the same.

This invention relates to pants or trouser stretchers, and particularly to the types that are expansible and insertible in the trouser legs, and an object of the invention is to 15 provide a device of this kind comprising a pair of elongated bars or members adapted to correspond to the front and rear of each trouser leg when flat, and being connected by yieldable or expansible spring 20 means, so as to hold said members or bars with their outer edges engaging the inner portion of the forward and rear parts of each trouser leg, so as to stretch the trouser leg and hold it in shape, and form creases 25 in the forward and rear parts of the trouser leg. By this yieldable or expansible spring means the trouser leg is stretched sufficiently to remove the wrinkles.

In practical fields the details of construction may necessitate alterations, falling 30 within the scope of what is claimed.

The invention comprises further features and combination of parts, as hereinafter set forth, shown in the drawings and claimed.

35 In the drawings:

Figure 1 is a view showing the improved pants stretcher as applied, showing the pants or trousers in section.

Fig. 2 is a view in elevation showing the 40 trouser or pants stretcher removed from the trouser leg, and illustrating the elongated members or bars farther apart than when inserted in the pants or trouser leg.

Fig. 3 is a transverse sectional view on line 45 3—3 of Fig. 1.

Referring more especially to the drawing, 1 designates the front pants stretching member or bar and 2 denotes the rear pants stretching member or bar. The member or 50 bar 1 in cross section tapers to sharp forward edge 3, and is of a shape longitudinally, to conform to the shape of the forward part of the trouser leg. The member or bar 2, in cross section, tapers to a rear 55 sharp edge 5, and is of a shape longitudi-

nally, to conform to the contour of the rear part of the trouser leg.

Spring members 6 and 7 are provided, which are bent upon themselves to form the spring loops 8 and 9, which tend to cause the arms of the spring to spring or expand forwardly and rearwardly, to cause the elongated members or bars 1 and 2 to spring forwardly and rearwardly to contact between the surface of the forward and rear 65 parts of the trouser legs, thereby stretching the trouser legs and causing creases to be formed. The arms of the spring members 6 and 7 have their extremities or ends adjustably connected to the bars 1 and 2, so 70 that the spring members may be adjusted, said adjustable connections of the arms being designated by the characters 10. For instance, should it be desired that the spring action or the outward pressure of the lower 75 parts of the bars 1 and 2 be decreased, the spring member 6 may be adjusted toward the spring member 7, and should it be desired that said spring action or outward pressure of the lower part of the members 80 1 and 2 be increased, the spring member 6 may be adjusted toward the lower parts of the bars 1 and 2. The spring member 7 may be correspondingly adjusted. It is to be noted that the arms of said spring members are connected substantially adjacent the central portions of the bars or members 85 1 and 2, so that the greatest pressure or spring action is upon the knee portions of the trouser leg, where the greatest wrinkles 90 and bagging of the trouser leg occurs, and by this excessive pressure and stretching action, the bagging and wrinkles at the knee portion of the trouser leg are readily removed. The inner edge of member or 95 bar 2 adjacent its opposite ends is provided with eyes 11, to which the eyes 12 of the rods 13 and 14 are connected. Each rod consists of two sections 15 and 16, connected by a turn buckle 17, and the end portion 100 18 of the section 16 terminates in a lateral hook 19, which connects to an elongated opening 20 in the plate 21, on the inner edge of the bar or member 1, so as to hold said members 1 and 2 in their proper positions 105 relative to each other, to fit within a trouser leg. The looseness of play of the hook 19 in the opening 20 enables the members 1 and 2 to have slight movements from each other, acting to stretch the trouser leg and 110

hold the same in perfect shape. By virtue of the turn buckles the bars or members 1 and 2 may be adjusted relative to each other to fit different widths of trouser legs.

5 The invention having been set forth, what is claimed as new and useful is:

1. A pants stretcher comprising oppositely disposed bars designed to engage the front and rear of the trouser leg and conforming in shape therewith, loop spring members connecting said bars and designed to be depressed to permit the stretcher to be inserted in the leg, means for adjusting the loop spring members as to their position on said bars, and means connecting said oppositely disposed bars to hold the loop spring members depressed.

2. A pants stretcher comprising oppositely disposed bars designed to engage the front and rear of the trouser leg and conforming in shape therewith, loop spring

members connecting said bars and designed to be depressed to permit the stretcher to be inserted in the leg, means connecting said oppositely disposed bars to hold the loop 25 spring members depressed, and means for adjusting the loop spring members as to their position on said bars, said adjusting means comprising recesses formed in the bars, clamps attached to the loop spring 30 members and engaging the recesses on the bars and set screws for holding the clamps and with them the loop spring members in any of their adjusted positions.

In testimony whereof I have signed my 35 name to this specification in the presence of two subscribing witnesses.

WALTER TAYLOR.
